UNITED STATES PATENT OFFICE.

JOSEPH WEISS, OF BISON, KANSAS.

TOY.

1,123,633.

Specification of Letters Patent.

Patented Jan. 5, 1915.

Application filed July 31, 1913. Serial No. 782,368.

To all whom it may concern:

Be it known that I, JOSEPH WEISS, a citizen of the United States, residing at Bison, the county of Rush and State of Kansas, have invented certain new and useful Improvements in Toys; and I do hereby declare the following to be a full, clear, and exact description of the invention, such as will enable others skilled in the art to which it appertains to make and use the same.

This invention relates to toys, and particularly to that class of toys which are adapted to be operated by the action of the wind.

One of the principal objects of my invention is to provide a toy of this class which will afford amusement to its user, and which may be used as an advertising device.

20 A further object of my invention is to provide a toy of the class specified, which will be simple, durable, efficient in operation, and inexpensive to manufacture.

These and other objects may be attained 25 by means of my invention, which consists in the construction, combination and arrangement of parts hereinafter more fully described and claimed, and illustrated in the accompanying drawing, in which like reference characters indicate like parts throughout the several views, and in which,

Figure 1 is a perspective view of a toy constructed according to my invention. Fig. 2, is a vertical transverse sectional view 35 thereof. Fig. 3, is a perspective view of the upper end of the vertical rod. Fig. 4, is a fragmentary view similar to Fig. 2, and showing a modification of the device.

In carrying out the preferred embodiment 40 of my invention, I provide a figure 5, which may be constructed of wood or tin or other suitable material, and which is here shown as being in the form of a soldier or guardsman, painted to represent a uniform. Extending transversely through the body of 45 the figure at a point slightly rearward of the medial line thereof, and at the shoulders of the figure, is provided a metal pin 6, which is rotatable within the body and has oppositely extending arms 7, secured to its 50 ends, said arms being slightly spaced from the shoulders of the figure, by means of metal washers 8. To the outer ends of the arms 7, are secured paddles or blades 9 and 55 10, the blade 9, being parallel with a plane which cuts the figure vertically from front

to rear thereof, and the paddle 10 being parallel with a plane which cuts the figure vertically crosswise thereof, it being apparent therefore that the blades or paddles are set at right angles to each other.

The body of the figure is centrally and vertically bored, and in the lower portion of the bore is positioned a vertical shaft 11, which is formed at its lower end with a flange 12, and a screw 13, whereby the shaft may be secured to a bracket 14, or to some other suitable object. The outer portion of the vertical bore, is reduced and forms a shoulder 15, at its junction with the lower portion of the bore, and in the upper reduced portion, is seated a second vertical shaft 16, which is smaller in diameter than the shaft 11, and which may be formed integrally therewith, or may have its lower end secured in a recess in the upper end of the shaft 11, the lower end of the shaft 16 and the upper end of the shaft 11, forming a shoulder at 17. A metal washer 18, through which the shaft 16 extends, is positioned in the bore between the shoulder 15 thereof, and the shoulder 17, of the shaft 11.

The head 19, of the figure may be hollow, or may as shown, be provided with a circular recess 20, adapted to be closed at its upper end by a cap 21, and within which is contained a cup member 22, which is secured to the upper end of the shaft 16, and which as shown, does not contact at any point with any portion of the walls or bottom of the recess 20, or with the cap 21. The head of the figure may be carved or painted to represent a face, and at the point where the eyes occur, apertures are made in the head, and these apertures are adapted to disclose painted pairs of eyes 23, on the cup member 22. At the lower ends of the legs 24, of the figure, a metal horizontally disposed plate 25 is secured by means of nails or screws 26, and this plate is apertured centrally to slidably receive the shaft 11.

It is of course to be understood that the pin 6, is rotatable in the body of the figure, and that the body is rotatable on the shafts 11 and 16, the weight of the body occurring at the washer 18, the bore through which said shafts extend, being of such a diameter, to allow rotation of the body with as little friction as possible. As the body rotates, it is evident that the pairs of eyes 23 will be disclosed through the openings in the head of the figure, and this effect combined

with the peculiar antics of the toy, will produce a novel and amusing effect. If it is so desired, advertising matter may be painted or printed on the paddles 9, or on the body of the figure.

In Fig. 4, is shown a modification, wherein the vertical bore terminates at the upper end of the shaft 11, the latter having its upper end rounded as at 27, and adapted 10 to bear against the smooth head of a tack or nail 28, which is embedded in the body at the upper end of the vertical bore, thus forming a practically frictionless bearing. It is to be understood that in this modification, the shaft 16 and cup member 22, are dispensed with.

The parts of the device, it is to be understood, are so proportioned and arranged, as to place the center of gravity in the longitudinal axis of the vertical shaft on which the body rotates. Should the figure be placed in a draft of wind, the wind acting on the paddles 9 and 10, will cause the figure to rotate and the paddles to rotate with the pin 25 6, but it is to be understood that the action of the toy is not uniform, but is irregular, the figure turning first in one direction, and then in the other, or perhaps turning in one direction for quite a while, the arms mean- 30 time assuming various angles and positions.

Although I have described the preferred embodiments of my invention, I reserve and may exercise the right to make such changes in the construction, combination and arrangement of parts, as do not depart from

the spirit of the invention and the scope of the appended claims.

Having thus fully described my invention, what I claim as new and desire to secure by Letters-Patent is,

1. In a device of the class described, a body, a shaft journaled therein, said body being rotatable on said shaft and being formed to represent a human figure, and having openings therein where the eyes 45 should occur, a cup member secured on said shaft and having eyes represented thereon, and means for rotating said body, whereby the eyes will be disclosed through the openings in the head of the body. 50

2. A device of the character described, a body, a shaft journaled in said body, an eye device at the top of said shaft, apertures in the head of said body registering with said eye device, a transverse shaft through 55 said body, arms attached to the end of said transverse shaft in an opposite direction, blades extended from said arms, one blade being extended from the plane of said device and one blade being extended at right 60 angles thereto and means to independently rotate said arms to said body and rotate said body to said shaft.

In testimony whereof I have signed my name to this specification in the presence of 65 two subscribing witnesses.

JOSEPH WEISS,

Witnesses:

C. W. CHADDOCK,
D. M. ROTHWEILER.
